BEVERAGE DISPENSER

Jacob Levin, New York, N. Y.

Application July 12, 1950, Serial No. 11,088

Term of patent 14 years

(Cl. D2—3)

To all whom it may concern:

Be it known that I, Jacob Levin, a citizen of the United States, residing at the city of New York, county of Bronx, State of New York, have invented a new, original, and ornamental Design for a Beverage Dispenser, of which the following is a specification, reference being had to the accompanying drawing, forming part thereof.

The figure is a perspective view of a beverage dispenser, showing my new design. The sides not shown are like those which are shown and the top of the large cylindrical housing is substantially plain.

I claim:

The ornamental design for a beverage dispenser, as shown and described.

JACOB LEVIN.
